(57) **CLAIM**

The ornamental design for a license plate frame, as shown and described.

DESCRIPTION

FIG. 1 is a perspective front view showing our new design for a license plate frame.

FIG. 2 is a magnified view of a portion of the license plate frame shown in FIG. 1.

FIG. 3 is a front view of the license plate frame of the present invention.

FIG. 4 is a back view of the license plate frame of the present invention.

FIG. 5 is a right side view of the license plate frame of the present invention.

FIG. 6 is a top view of the license plate frame of the present invention.

FIG. 7 is a front view showing a second embodiment of our design for a license plate frame, with the only difference compared to the first embodiment being an emblem on the bottom bar of the frame shifted downward from the position of that emblem in the design shown in FIG. 1; and, FIG. 8 is a back view of the license plate frame shown in FIG. 7.
